INVENTOR

Archibald Martin

UNITED STATES PATENT OFFICE

ARCHWORTH MARTIN, OF BELLEVUE, PENNSYLVANIA, ASSIGNOR TO UNITED STATES ENVELOPE COMPANY, OF WORCESTER, MASSACHUSETTS, A CORPORATION OF MAINE

ENVELOPE

Application filed March 4, 1927, Serial No. 172,690. Renewed February 15, 1930.

This invention relates to envelopes for mailing purposes, and more particularly to those which embody, in an integral or a unitary structure, two separate compartments, the purpose being to provide a double or duplex envelope for the transmission of two different classes of postal matter, mailable at different rates of postage.

My invention contemplates the provision of an envelope having a main compartment for receiving catalogues, merchandise, automobile license plates, etc., and a pocket for statements, invoices, letters, etc., which may be conveniently formed of a single sheet of material and so arranged that the compartment and pocket are conveniently accessible for the insertion of the matter to be shipped or transmitted.

Another object of my invention is to provide a two-compartment envelope of such form that it may be readily made on automatic machines, such as those now employed in making various types of envelopes.

Other and further objects and advantages of the invention will be made apparent by the following detailed description thereof, taken in connection with the accompanying drawings, in which, Figure 1 is a plan view of the blank from which the envelope of my invention may be made, and Figure 2 is a plan view of the completed envelope made from the blank of Figure 1, the same being shown folded and sealed and ready for mailing.

The blank comprises a main body portion 3 and a supplemental body or back portion 4 that is foldable on the broken line 5 to overlie the main body portion 3. The blank further comprises a flap 6 here shown as extending from one edge of body portion 3, and preferably providing a window opening 7 adapted to reveal the address on an enclosure within the envelope pocket provided, as hereinafter described, by said flap 6; the latter, following the inward folding of back portion 4 on body portion 3, is folded inwardly on the broken line 5' to overlie the lower part of the back portion 4 and its gummed portions 8 caused to adhere thereto; in this way, a pocket is formed on the

outside of back portion 4 between the zones of adhesion 8, 8' of the flap 6, the entrance to said pocket, for the insertion therein of a letter or the like being along the edge of flap 6 between the adhesively secured end portions of said edge. The blank also provides a sealing flap 9 which projects from the opposite edge of the body portion 3 and is foldable inward over the portion 4, either before or after the end flap 10 is folded over the free end of the body portion 4. Catalogs or other matter will be inserted into the space between the body portions 3 and 4, either past the flap 9 or past the flap 10. The flap 9 may be gummed, if desired, as indicated at 11, to hold the body portion 4 in position, but I may prefer to omit the gumming at this point, since the body portion 4 can be otherwise held in position, as hereinafter described.

The sealing flap 9 is gummed at 12, so that when folded to the position shown in Fig. 2, it will overlie the inner edge of the pocket flap 6 and adhere to such flap and also to the body portion 4; thus the gumming 12 serves not only to hold the body portion 4 in position, but also serves to retain mail matter in the pocket, the address on the contents of the pocket being readable through the opening 7.

In cases where it is desired to insert the merchandise or catalogs past the flap 9, the flap 10 can be sealed as soon as the portions 4 and 6 have been folded, or if desired said flap 10 can be left unsealed, to permit postal inspection of the contents of the large compartment; on the other hand, if it is desired to insert the contents through the end of the envelope, the flap 10 will not be sealed immediately, but the flap 9 will be first folded over the back 4 and sealed at 11. After insertion of the goods, the flap 10 would be then folded and either sealed, or left unsealed for postal inspection. The gummed portion 12 of the flap 9 will be brought against the pocket flap 6 and sealed, upon insertion of a letter or the like within the pocket, either before or after the insertion of merchandise in the large compartment.

From the foregoing it will be seen that I

provide an envelope into which the goods can be inserted from either the side or the end, depending upon whether the flap 10 or the gummed portion 11 is temporarily left unsealed, and wherein the first class mail matter can be readily inserted in the pocket either before or after the merchandise has been placed in the large compartment. Also, the sealing flap for the pocket is formed separately from the pocket flap, thus permitting more convenient insertion of the letter mail than in those envelopes wherein such sealing flap is formed on one edge of the pocket flap.

I claim as my invention:—

- 15 1. A duplex envelope having a main body portion, a supplemental body portion cooperating with the main body portion to form a compartment, a pocket flap connected to an edge of one of said body portions and folded inward, said flap being gummed for only a portion of its length to form a pocket, and a sealing flap secured to the opposite edge of the main body portion and folded into position to overlie a portion of the supplemental body portion and the inner edge of the unconnected portion of the pocket flap to form a closure for said pocket, the said sealing flap being gummed adjacent to its line of fold for holding the supplemental body portion in place and being gummed on that portion of its surface which overlies the said unconnected portion of the pocket flap.

- 20 2. A duplex envelope made from a single sheet or blank, the latter having a main body portion and a supplemental body or back portion which is folded to overlie and form a compartment with said main body portion, said blank providing along one edge of the main body portion a pocket flap which is folded to overlie and form a compartment with said supplemental body portion, said flap being secured by adhesive to said supplemental body portion for only a portion of its length, thereby to provide an entrance to said second-mentioned compartment, and a sealing flap extending from the opposite edge of the main body portion and adapted to be folded in to overlying relation to the supplemental body portion and to the free or unconnected edge portion of said pocket flap, the said sealing flap being gummed along its free edge for adhesion of same jointly to the unconnected edge portion of the pocket flap and the adjacent surface of the supplemental body portion, thereby to close and seal the entrance to the second-mentioned compartment and at the same time to hold the supplemental body portion against displacement.

In testimony whereof, I, the said ARCHWORTH MARTIN, have hereunto set my hand.

ARCHWORTH MARTIN.
